ROLLING MILL

John H. Jaecker, Massillon, and Howard J. Findley, Shaker Heights, Ohio, assignors to The Eaton Manufacturing Company, Cleveland, Ohio, a corporation of Ohio

Application October 6, 1943, Serial No. 505,138

11 Claims.

(Cl. 80—34)

This application relates to rolling mills and more particularly to an improved form of mill with which wire stock can be efficiently rolled to a desired size and cross sectional shape.

One of the uses for such rolled stock is the manufacture of lock washers and when used for this purpose, it is desirable that the stock have a quadrangular cross sectional shape in which one or more sides are inclined so that the stock has a tapered cross section. Heretofore in the rolling of such stock, the desired taper has been obtained by using rolls having their peripheral faces ground to the inclination of the desired taper or bevel. However, the use of rolls of this kind has numerous disadvantages which the present invention seeks to overcome. Among such disadvantages is the fact that when the taper of the stock is to be changed, the rolls must be dismounted and their surfaces ground to the new taper angle. This involves a considerable amount of labor and decreases the life of the rolls and also interrupts production operations.

It is, therefore, an object of the present invention to provide an improved rolling mill of this character having rolls of novel form and novel roll mounting means enabling the rolls to be readily shifted to different inclined positions according to the shape and taper desired for the stock being rolled.

Another object of the invention is to provide an improved rolling mill of the character mentioned, in which individual electric motors are employed for driving the respective rolls.

Still another object of this invention is to provide an improved rolling mill of the character referred to, having a group of disk-like rolls and in which the rolls are relatively inclined and each roll has an undercut side-face extending into partial overlapping relation to the working face of an adjacent roll.

The invention may be further briefly summarized as consisting in certain novel combinations and arrangements of parts hereinafter described and particularly set out in the appended claims.

In the accompanying sheets of drawings:

Fig. 1 is a front elevation showing a rolling mill constructed according to the present invention.

Fig. 2 is a partial front elevation with portions in section, showing the mounting and driving means for one of the rolls on a somewhat larger scale.

Fig. 3 is a partial side elevation of the roll mounting and driving means shown in Fig. 2.

Fig. 4 is a sectional view taken on line 4—4 of

Fig. 3 and further illustrating the roll mounting and driving means.

Fig. 5 is another sectional view thereof taken on line 5—5 of Fig. 4.

Fig. 6 is a detail sectional view, taken through one of the adjusting screws as indicated by line 6—6 of Fig. 2, and

Fig. 7 is another such detail sectional view taken on line 7—7 of Fig. 6.

10 Proceeding with a more detailed description of the invention and referring particularly to Figs. 1 and 2 we show our mill as comprising a suitable frame 10 and a group of four cooperating rolls 11, 12, 13 and 14 of novel form and disposed so

15 that their peripheral work-engaging faces define a quadrangular pass 15 for the stock S being rolled. The frame 10 is here shown as being an upright quadrangular plate or slab having a central opening 16 for passage of the stock therethrough.

20 The rolls are driven in a novel manner by individual electric motors 17, as explained in greater detail hereinafter, and a novel mount 18 is provided for each roll for mounting the same on the frame 10 in a manner to readily permit

25 adjustments of the roll positions for varying the cross sectional shape of the stock being rolled.

As shown in Fig. 2 and indicated above, the rolled stock S has a quadrangular shape and in this instance has two substantially parallel side

30 faces 19 and 20 and two side faces 21 and 22 which are relatively inclined so that the stock has a desired taper. With the form of roll and roll mounting means to be hereinafter described, the cross sectional shape of the stock can be varied

35 by shifting one or more of the rolls so as to change the relative inclination thereof. Ordinarily in the use of our mill the stock or wire is initially round and is changed to the desired cross-sectional shape, such as that shown in Fig. 2, by a

40 single passage through the rolls.

The rolls 11, 12, 13 and 14 are of disk-like form having cylindrical stock-engaging peripheral faces 11a, 12a, 13a and 14a. Each of the rolls is mounted on an enlarged section 24 of a drive shaft 25

45 which is supported in a pair of spaced bearings 26. The rolls are disposed in an annular or star-like group such that the axes of the shafts 25 all lie substantially in a common plane which is substantially parallel to the plane of the plate or slab

50 10. The adjacent portions of the disk-like rolls extend into meeting relation to define the pass 15 and in so doing each roll extends into partial overlapping relation to an adjacent roll. Thus,

55 as shown in the drawings, the side face 11b of the roll 11 extends into partial overlapping rela-

tion to the peripheral face 12a of the roll 12 and the side face 12b of the roll 12 extends into partial overlapping relation to the peripheral face 13a of the roll 13. Similarly the side face 13b of the roll 13 extends into partial overlapping relation to the peripheral face 14a of the roll 14 and the side face 14b of the roll 14 extends into partial overlapping relation to the peripheral face 11a of the first roll of the annular group of rolls.

To permit of the above mentioned shifting of the rolls to vary their relative inclination and to provide an operating clearance between the meeting portions of the rolls, the overlapping side face of each roll has a sloping annular recess or undercut 28 therein. As shown in the drawings, this undercut is formed only in the overlapping side face of each roll and starting at the peripheral face of the roll, becomes progressively deeper as the shaft 25 is approached.

The mounting and driving means for the four rolls 11, 12, 13 and 14 are substantially identical and, to avoid repetition, we will describe only the mounting and driving means for the roll 11. As shown in the drawings, the mounting means 18 provides three different adjustments for the roll 11. Two of these adjustments are substantially the same as have been provided heretofore in rolling mills of this kind and consist in a straight line substantially edgewise movement of the rolls toward and from each other for opening and closing the pass 15. The second adjustment also consists in a straight line movement by which the rolls can be moved sidewise in the direction of the axes of their shafts 25 or, in other words, a movement at substantially right angles to the first mentioned straight line movement. The third adjustment for the rolls is distinctly new and provides for a relative rocking or tilting by which the relative inclination of the rolls can be varied for changing the taper of the stock S.

The mounting means 18 by which these adjustments of the roll 11 are obtained comprises a yoke or carriage 30 having the spaced bearings 26 thereon, a slide or block 31 which carries the bracket 30 and a second slide 32 which carries the slide 31. The yoke 30 provides for the relative rocking movement of the roll, the slide 31 provides for the edgewise straight line closing and opening movement and the slide 32 provides for the straight line movement of the roll in the direction of the axis of the shaft 25.

As shown in Figs. 2 and 3, the frame or slab 10 carries a plate 33 which is bolted thereto and has a pair of dove-tail guideways 34 therein. The slide 32 has a pair of correspondingly spaced dove-tail projections 35 thereon, which slide in the ways 34 and provide for movement of the slide 32 in a direction to cause the above-mentioned closing and opening movements of the roll. Such movement of the slide 32 along the ways 34 is produced by an adjusting screw 36 having a threaded stem engaging in a threaded opening of a projection 31 of the slide. The adjusting screw 36 extends through, and is anchored in, a projection 38 of the plate 33 and adjacent its head 39 carries a graduated scale 40 which cooperates with a stationary reference line provided on the projection 38. In this instance the screw is anchored in the projection 38 by means of a clip 41 having a forked end which straddles a reduced section 36a of the screw. By rotating the screw 36 in the proper direction it will impart a pushing or pulling movement to the slide 32 and this will be transmitted through the slide 31 and the yoke 30 to the roll 11. The extent of

adjusting movement imparted to the roll can be observed or measured by the cooperation of the graduated scale 40 with the stationary reference line.

As already indicated, the slide 31 is mounted on the slide 32 and, for this purpose, we provide the slide 31 with a pair of spaced dove-tail projections 44 and provide the slide 32 with a pair of corresponding dove-tail guideways 45 in which such projections slidably engage. The guideways 45 extend at substantially right angles to the guideways 34 of the plate 33. To assist the dove-tail projections 44 in supporting the slide 31, we provide a retaining plate 46 which engages the opposite face of the slide 31 and is connected with the frame or slab 10 by clamping bolts 47 which extend through clearance openings 48 in the slide 31 and clearance slots 49 in the slide 32. After the desired adjustments of the slides 31 and 32 have been made, these bolts can be tightened to lock the slides 31 and 32 in fixed relation to the frame 10. As shown in the drawings, an adjusting screw 36 of the form above described is provided for imparting the desired movement to the slide 31 and cooperates with a fixed reference line 42.

The slide 31 carries the yoke 30 and to provide for the desired rocking movement of the yoke, we construct the slide 31 with an arcuate bearing face 51 and provide the yoke with a correspondingly curved shoe or base portion 52 which slidably engages such arcuate bearing face. The yoke 30 has spaced areas which straddle the roll 11 and carry the bearings 26 in which the shaft 25 is journaled. Rocking movement imparted to the yoke 30 produces a corresponding variation in the relative inclination of the roll 11.

The desired rocking movement can be imparted to the yoke 30 by means of an adjusting screw 53 which is carried by a projection 54 of the slide 31 and which cooperates with a nut 55 carried by one of the arms of the yoke. The adjusting screw 53 is anchored in a block 56 which is, in turn, connected with the projection 54 by means of trunnions 57 which permit swinging of the adjusting screw for proper cooperation with the nut 55. The screw 53 is anchored in the trunnioned block 56 by means of a clip 58 having a forked inner end engaging a reduced portion 59 of the screw stem. The nut 55 can also be rockably mounted on the yoke 30 by means of trunnions 60. When the yoke 30 has been shifted by the adjusting screw 53 an extent to produce the desired inclination of the roll 11, the yoke can be locked to the slide 31 by means of the clamping bolts 61 which extend through a slot 62 in the curved base 52 of the yoke and have their heads anchored in the slide 31. The adjusting screw 53 is also provided with a graduated scale 63 which cooperates with a stationary reference line on the projection 54 for indicating or measuring the adjustment of the roll 11.

As shown in the drawings, the yoke 30 carries a laterally projecting motor support 65 on which the electric motor 17 is mounted. The motor 17 is drivingly connected with one end of the shaft 25 by suitable gearing, such as a worm and a worm gear located in a gear casing 66 carried by the housing of the motor. As seen in Fig. 1, one of the electric motors 17 is provided for each of the rolls 11, 12, 13 and 14. These motors can be of any suitable construction and rating, for example, they can be direct current series wound motors although other types of motors could be used.

By providing an individual driving motor for each of the rolls 11, 12, 13 and 14, we obtain a more satisfactory operation because the rolls can operate at different speeds and the speed of each roll will be automatically adjusted according to the share of the work being performed by such roll. This is a very useful feature in our mill because in rolling tapered stock, the relatively inclined rolls necessarily operate at different peripheral speeds and if the rolls were all geared together relative sliding would occur and would probably result in damage to the rolls and to the surface of the stock. By using individual driving motors for the respective rolls, each roll can operate at its own speed depending upon the amount of stock being broken down or traversed by such roll and relative sliding between the roll and the stock is reduced to a minimum.

From the foregoing description and the accompanying drawings, it will now be readily seen, that we have provided an improved form of rolling mill having important advantages over similar mills heretofore employed. It will be seen also that in addition to the novel form provided for the rolls, we have provided novel roll driving and mounting means by which relative slipping between the rolls and the stock is reduced to a minimum and adjustment of the rolls can be quickly and easily made for changing the taper of the stock or other purposes without necessitating regrinding of the rolls or a lengthy interruption in the operation of the mill.

While we have illustrated and described our improved rolling mill in considerable detail, it will be understood, of course, that we do not wish to be correspondingly limited but regard our invention as including all changes and modifications coming within the spirit of the invention and the scope of the appended claims.

Having thus described our invention, we claim:

1. In a mill of the character described, two pairs of rolls having opposed peripheral faces of a substantially constant diameter thereacross and engageable with stock to be rolled and having their axes of rotation lying substantially in a common plane, each roll having an annularly extending undercut of varying depth in a side face thereof and contiguous to its peripheral face and being disposed in tilted relation to an adjacent roll with said undercut partially overlapping the peripheral face of said adjacent roll so that the rolls define a quadrangular pass in which at least one of the angles is other than a right angle.

2. In a mill of the character described, a group of cooperating disk-like rolls each having a peripheral face of a substantially constant diameter thereacross and engageable with the stock to be rolled and a side face having a sloping annularly extending undercut contiguous to its peripheral face, said rolls being relatively tilted and disposed with their axes of rotation lying substantially in a common plane and with the sloping undercut of each roll partially overlapping the peripheral face of an adjacent roll and with the uncovered portions of said peripheral faces defining a polygonal pass for the stock in which at least one of the angles is other than a right angle.

3. In a mill of the character described, a frame, a plurality of rolls having cooperating peripheral faces engageable with the stock to be rolled, and means mounting said rolls on said frame including carriages for the respective rolls, said frame having arcuate bearing surfaces thereon and said carriages having arcuate shoe portions slideable on said arcuate bearing surfaces to permit rock-

ing of the carriages for causing relative tilting of the rolls.

4. In a mill of the character described, a frame, a plurality of rolls having cooperating peripheral faces engageable with the stock to be rolled and each roll having an annularly extending undercut in a side face contiguous to its peripheral face and extending into partial overlapping relation with the peripheral face of an adjacent roll, and means mounting said rolls on said frame including carriages for the respective rolls, said frame having arcuate bearing surfaces thereon and said carriages having arcuate shoe portions slideable on said arcuate bearing surfaces to permit rocking of the carriages for causing relative tilting of the rolls.

5. In a mill of the character described, a frame, a plurality of rolls having cooperating peripheral faces of a substantially constant diameter thereacross and engageable with the stock to be rolled, means mounting said rolls on said frame including carriages for the respective rolls, a motor support on each carriage, and individual electric motors on the supports and connected with the respective rolls for driving the same, said frame having arcuate bearing surfaces thereon and said carriages having arcuate shoe portions slideable on said arcuate bearing surfaces to permit rocking of the carriages for causing relative tilting of said rolls.

6. In a rolling mill, a frame, a plurality of disk-like rolls having cooperating cylindrical peripheral faces of a substantially constant diameter thereacross and engageable with the stock to be rolled and each roll having a sloping annularly extending undercut in a side face thereof contiguous to its peripheral face, said rolls being disposed in relatively tilted relation with the undercut face of each roll extending into partial overlapping relation to the peripheral face of an adjacent roll and with the uncovered portions of said peripheral faces defining a polygonal pass for the stock, and means mounting said rolls on said frame so as to provide a plurality of adjustments for each roll including carriages for the respective rolls, said frame having arcuate bearing surfaces thereon and said carriages having arcuate shoe portions slideable on said arcuate bearing surfaces to permit rocking of the carriages for varying the relative tilt of said rolls.

7. In a mill of the character described, a frame, a group of cooperating disk-like rolls defining a polygonal pass for stock to be rolled, and mounting means for each roll comprising a slide movable relative to said frame, a second slide movable on the first-mentioned slide, and a carriage on the second slide and rockable relative thereto, said second slide having an arcuate bearing surface thereon and said carriage having an arcuate shoe portion slideable on said arcuate bearing surface to permit rocking of the carriage

8. In a rolling mill, a frame, a plurality of disk-like rolls having cooperating cylindrical peripheral faces engageable with the stock to be rolled and each roll having a sloping undercut in a side face thereof, said rolls being disposed in relatively tilted relation with the undercut face of each roll extending into partial overlapping relation to the peripheral face of an adjacent roll and with the uncovered portions of said peripheral faces defining a polygonal pass for the stock, and mounting means for each roll comprising a slide movable relative to said frame, a second slide movable on the first-mentioned slide, and

a carriage on the second slide and rockable relative thereto.

9. In a mill of the character described, a group of rolls each having a peripheral face of a substantially constant diameter thereacross and the rolls of said group being disposed with said faces in cooperating relation to define a pass for stock to be rolled, one roll of said group having in a side face thereof an annularly extending undercut contiguous to its peripheral face and said one roll being disposed in tilted relation to an adjacent roll of said group with such undercut portion of said side face partially overlapping the constant diameter peripheral face of said adjacent roll.

10. In a mill of the character described, a group of rolls each having a peripheral face of a substantially constant diameter thereacross and the rolls of said group being disposed with said faces in cooperating relation to define a pass for stock to be rolled, one roll of said group having in a side face thereof an annularly extending undercut of varying depth and contiguous

to its peripheral face, said one roll being disposed in tilted relation to an adjacent roll of said group with such undercut portion of said side face partially overlapping the constant diameter peripheral face of said adjacent roll so that the peripheral faces of said one roll and said adjacent roll define an angle other than a right angle.

11. In a mill of the character described, a group of cooperating rolls each being in the form of a disk having a peripheral face of a substantially constant diameter thereacross and engageable with the stock to be rolled, each roll of said group having an annularly extending undercut of varying depth in a side face thereof and contiguous to its peripheral face, the rolls of said group being disposed relative to each other so that the undercut side face of each roll partially overlaps the constant diameter peripheral face of an adjacent roll and so that the uncovered portions 20 of said constant diameter peripheral faces define a polygonal pass for the stock.

JOHN H. JAECKER.
HOWARD J. FINDLEY.
